(57) **CLAIM**

The ornamental design for a portion of a display screen with a user interface, as shown and described.

DESCRIPTION

FIG. 1 is a front view of a portion of a display screen with a user interface showing a first embodiment of our new design; and,

FIG. 2 is a front view of a portion of a display screen with a user interface showing a second embodiment of our new design.

The broken line showing of the portion of the display screen is included for the purpose of illustrating the unclaimed environment of the user interface and forms no part of the claimed design. The broken lines defining the five unclaimed rectangular regions represent boundary lines and form no part of the claimed design.
